UNITED STATES PATENT OFFICE.

JESSE S. JONES AND JAMES H. DAUGHERTY, OF MATSON, MISSOURI.

BUNDLE-TYING MACHINE.

1,119,285.

Specification of Letters Patent.

Patented Dec. 1, 1914.

Application filed April 18, 1914. Serial No. 832,923.

To all whom it may concern:

Be it known that we, JESSE S. JONES and JAMES H. DAUGHERTY, citizens of the United States, residing at Matson, in the county of St. Charles and State of Missouri, have invented certain new and useful Improvements in Bundle-Tying Machines, of which the following is a specification, reference being had to the accompanying drawings.

10 This invention relates to improvements in machines for tying bundles, and an object thereof is the provision of a device of this character in which means are provided for automatically twisting the ends of the tying 15 wire tightly around the bundle and severing the twisted ends of the wire closely adjacent to the bundle in one operation.

Another object of this invention is the provision of a device for tying bundles 20 which consists of a portable standard to which an outwardly and upwardly extending arm is connected, the arm being adapted to receive and support a bundle of grain, the standard carrying means to receive the ends 25 of the wire disposed around the grain, the standard also carrying a vertically movable bar which, upon movement in the proper direction, is adapted to twist the ends of the wire around the bundle, and to sever the 30 twisted ends closely adjacent the bundle.

With these and other objects in view, our invention consists in the novel construction, combination, and arrangement of parts to be hereinafter more fully described, claimed, 35 and illustrated in the accompanying drawing, in which,

Figure 1 is a front elevation of my device; Fig. 2 is a side elevation thereof, partly in section; and Fig. 3 is a detail transverse 40 section, showing the manner of mounting the vertically movable bar and the roller in the standard.

Referring more particularly to the drawing, the numeral 1 designates a standard, 45 and 2 a supporting arm which extends upwardly from the lower end of the standard in parallel relation therewith for a portion of its length, the upper end of the arm 2 being curved outwardly and upwardly as at 50 3 to form a seat for a bundle of grain. The standard 1 has a longitudinal groove 4 formed in its forward face, the groove extending from the top of the standard to a point adjacent the lower end thereof, and 55 mounted for vertical movement in the groove is a bar 5 which is formed with a handle 6 at its upper end. The bar is

formed with a series of transversely extending teeth 7, the teeth extending from a point intermediate of the ends of the bar to its lower end. Connected to one side of the standard 1 intermediate of its ends is an angular bracket plate 8, one arm of the bracket plate extending forwardly of the bar and having an aperture 9 therein, the other arm 65 of the bracket plate 8 extending laterally from the standard as at 10, and having a spool holder 11 connected to its outer extremity. Connected to the opposite side of the standard 1 is a bowed supporting bar 12 70 which is provided intermediate of its ends with a forwardly extending arm 13 inwardly of which is connected a bracket 14, the bracket 14 having an opening 15 therein which is in transverse alinement with the 75 opening 9 in the bracket plate 8. Rotatably mounted in the transversely alined openings 9 and 15 of the brackets 8 and 14, respectively, are the reduced ends 16 of a toothed roller 17, the teeth of the roller 17 meshing 80 with the teeth 7 on the vertically movable bar 5.

The roller 17 is formed with a pair of longitudinally extending bores 18 and 19 which are disposed to one side of the axial center 85 of the roller, and which extend entirely through the same. Rotatably mounted in the spool holder 11 is a spool 20 upon which a roll of wire 21 is carried, the free end of the wire being passed through the bore 19 in 90 the roller and is connected adjacent its extremity between the diverging gripping arms 22 on the upper extremity of the supporting arm 2, the upper extremity of the arm being disposed in horizontal alinement 95 with the roller 17. Pivotaly connected adjacent one end to the bowed supporting bar 12 is a knife blade 23, the forward end of the blade 23 being normally disposed above the adjacent end of the roller 17 and being 100 maintained in this position by a coil spring 24 which is connected at one end to the knife blade 23 forwardly of its pivotal point, and at its other end to the bar 12 above its pivotal point as clearly shown in the drawing. 105 Connected at its upper end to the bar 5 above the toothed portion thereof, is a knife operating arm 25, the lower end of which is offset outwardly and laterally as at 26 so that the free end of the arm 25 is disposed 110 above the forward end of the knife blade 23 in a position to strike the same upon downward movement of the bar 5.

In the practical use of my device, the bar

5 is moved to its uppermost position, and the free end of the wire 21 mounted upon the roller 20 is passed through the bore 19 in the roller 17, and is connected adjacent its 5 extremity between the gripping arms 22 on the upper extremity of the supporting arm 2. The bundle of grain or similar material which is to be tied is then placed upon the wire 21 which is disposed above the arm 2 10 so that upon downward movement of the bundle, the wire is unwound from the roller around the lower portion of the bundle. When the bundle is in this position upon the outwardly extending portion of the arm 2, the wire is removed from the gripping arms 22 and the extremity of the wire is 15 passed through the bore 18 in the roller; and upon downward movement of the bar 5, the ends of the wire are twisted tightly 20 against the bundle of grain by reason of the rotation of the roller 17, and upon further downward movement of the bar 5, the arm 25 strikes the knife blade 23 and forces the same downwardly to sever the twisted wires 25 closely adjacent the bundle. After the twisted wire has been severed, the tied bundle may be removed from the supporting arm 2, and the bar 5 again raised to its uppermost position, whereupon the operation 30 may be repeated.

From the above description, taken in connection with the accompanying drawing, it will be seen that we have provided a portable bundle tying machine which is extremely simple in construction, whereby the same may be cheaply manufactured, and one which will fulfil all of the requirements of such a device.

Having thus fully described our invention, what we desire to secure and claim by Letters Patent, is:—

1. A device of the class described comprising a standard, a supporting arm carried by the standard, a vertically movable bar carried by the standard, said bar being provided with teeth for a portion of its length, a toothed roller carried by the standard and meshing with the teeth on said bar, and a knife pivotally connected to the standard, said knife being adapted for movement upon operation of the bar in one direction, for the purpose described.

2. A bundle tying machine comprising a standard, a toothed roller carried by the standard, a vertically movable bar carried by the standard and having teeth meshing with the teeth of said roller, means connected to the standard for carrying a spool of wire, said roller having a pair of bores extending therethrough, the bores being adapted to receive the wire whereby the wire may be extended through one of the bores

for engagement around a bundle and the extremity of the wire passed through the other of said bores, so that upon movement 65 of the bar the wire may be twisted around the bundle.

3. A bundle tying machine comprising a standard, a supporting arm connected to the lower end of the standard, a toothed roller carried by the standard, a vertically movable bar carried by the standard and having teeth meshing with the teeth of said roller, said roller having a pair of bores extending therethrough, means connected to the standard for supporting a spool of wire, said bores being adapted to receive the wire therethrough, whereby the wire may be passed through one of the bores and engaged around a bundle carried upon the supporting arm, and the extremity of the wire may be passed through the other of said bores, so that upon movement of the bar the wire will be twisted around the bundle, and means for severing the twisted wire adjacent the bundle.

4. A bundle tying machine comprising a standard, a supporting arm connected to the standard at its lower end, a roller carried by the standard intermediate of its ends and having a pair of parallel bores extending therethrough, means connected to the standard for supporting a spool of wire, said bores being adapted to receive the wire therethrough, whereby the wire may be 95 passed through one of the bores and disposed around a bundle carried upon the supporting arm, and the wire may then be passed through the other of said bores, and means for rotating said roller whereby to 100 twist the wire around the bundle.

5. A bundle tying machine comprising a standard, a roller carried by said standard and having a pair of parallel bores extending therethrough, means connected to the 105 standard for supporting a spool of wire, said bores being adapted to receive the wire therethrough, whereby the wire may be passed through one of the bores and disposed around a bundle and thence passed 110 through the other of said bores, means for rotating said roller whereby to twist the wire around said bundle, and means carried by the last mentioned means for severing the twisted wire.

In testimony whereof we hereunto affix our signatures in the presence of two witnesses on this the 11th day of April 1914.

JESSE S. JONES.
JAMES H. DAUGHERTY.
